United States Patent

Des. 236,587
Patented Sept. 2, 1975

236,587

BOTTLE

Edward J. Kretz, Toledo, Ohio, assignor to Owens-Illinois, Inc.

Filed Sept. 20, 1973, Ser. No. 398,968

Term of patent 14 years

Int. Cl. D9—01

U.S. Cl. D9—155

FIG. 1

FIG. 2

FIG. 3

FIG. 1 is an elevational view of a bottle showing my new design;

FIG. 2 is a top plan view thereof; and

FIG. 3 is a bottom plan view thereof.

The side opposite that seen in FIG. 1 is the same in appearance as the side shown.

I claim:

The ornamental design for a bottle, substantially as shown and described.
